UNITED STATES PATENT OFFICE.

JOHN CARMICHAEL AND RALPH WHIPPS, OF NORTH VANCOUVER, BRITISH COLUMBIA, CANADA.

DEVICE FOR PULLING ON SHOES.

1,116,797.

Specification of Letters Patent. Patented Nov. 10, 1914.

Application filed April 29, 1914. Serial No. 835,212.

To all whom it may concern:

Be it known that we, JOHN CARMICHAEL and RALPH WHIPPS, both subjects of the King of Great Britain, and both residents 5 of the city of North Vancouver, in the Province of British Columbia, Canada, have invented certain new and useful Improvements in Devices for Pulling on Shoes, of which the following is a specification.

10 Our invention relates to improvements in devices for pulling on shoes, and the object of our invention is to devise a simple and inexpensive means whereby the shoe can be easily pulled on to the foot without bending 15 the body, thereby overcoming the disadvantages pertaining to the action of putting on shoes at the present time, necessitating bending, which, while of no great trouble to a person in normal condition, is a source 20 of considerable discomfort and inconvenience to persons inclined to corpulency or those in a frail state of health. Our device, while of great convenience to all persons, is specially beneficial to corpulent persons, invalids, and those to whom bending is a 25 source of discomfort and inconvenience. We attain this object by the means illustrated in the accompanying drawings in which—

30 Figure 1 is a perspective view of our device, shown in open position. Fig. 2 is a perspective view, showing our device in a closed position. Fig. 3 is a view showing the practical application of our device.

35 Similar figures of reference indicate similar parts throughout the several views.

1 represents one of the gripping members of our device, on the inside face of which and in proximity to the lower end thereof 40 is secured a piece of serrated rubber 2 or other suitable gripping material, as shown more particularly in Fig. 1.

3 represents the other gripping member of our device, the lower end of which is 45 folded backwardly on an inclined plane so that the point will lie along the outer face of the member, thus forming a substantially wedge-shaped portion 4 on the lower end of the member 3 and on the outside thereof.

50 5 is a piece of rubber or other gripping material secured on the inside face of the member 3 as shown in Fig. 1, which rubber 5 is designed to co-act with the rubber 2 on

the member 1 when the device is in the closed position, as shown more particularly 55 in Fig. 2.

6 is a bridging member, formed integrally with the member 1 and adapted to straddle the member 3 to act as a guide for the wedge shaped portion 4 and also to allow the members 1 and 3 to separate sufficiently while at the same time holding them together at their lower extremities, all as shown in Fig. 1.

7 is the handle of our device, formed of 65 suitable shape, such as shown in Fig. 1, which handle is disposed between the members 1 and 3 at the upper extremities thereof and secured thereto by the pins 8 and 9. These pins 8 and 9 are free to swivel in 70 their respective members 1 and 3, and are secured into the handle 7 in eccentric position with relation to each other, as shown more particularly in Fig. 2.

Having thus indicated the principal parts 75 of our invention we will now describe the manner in which it is used. Referring now particularly to Fig. 2, in which our device is shown closed, the opening is effected by turning the handle 7 down, this action caus- 80

ing the member 3 to move downwardly and allowing the gripping points of the members 1 and 3 to become separated, all as shown clearly in Fig. 1. The top edge of the shoe is now placed between the gripping 85 points, after which the handle 7 is straightened up, thus drawing the member 3 upwardly, the wedge portion 4 then coming into action against the bridging member 6 to force the points of the members 1 and 3 90 together to clamp the shoe firmly between the rubber portions 2 and 5 respectively. The foot may then be inserted, and the shoe pulled on by means of the device without the necessity of bending the body. In put- 95

ting on slippers or low shoes, one such device may be used; for boots it is preferable to use two devices, one on each side, the manner of use being clearly shown in Fig. 3. It will be seen, therefore, that we have de- 100

vised a simple, inexpensive, and efficient means whereby shoes may be pulled on to the feet without the necessity of bending the body to do so, the use of which provides a great convenience for all persons and which 105 is specially beneficial for corpulent persons,

invalids, and those to whom bending is a particular source of inconvenience and distress.

What we claim as our invention is:

- 5 1. A device of the class described comprising in combination, a pair of oppositely disposed gripping members the lower inner portions of which are faced with suitable gripping material, a wedge member carried 10 by one of said gripping members, a bridging member carried by the other gripping member and straddling the said wedge member, and a suitable handle having said gripping members pivoted thereto at different positions thereon whereby pivotal movement of 15 said handle separates or brings together the gripping members to open or close the device.
2. A device of the class described, comprising, in combination, a pair of rod members having their lower inner points formed as opposing gripping portions, the lower end of one rod being extended beyond its

gripping portion and doubled back to form a wedge portion, a bridging member carried 25 by the other rod member and straddling the said wedge portion, and a suitable handle disposed between the upper ends of the said rod members and to which the said members are pivotally connected at different 30 points thereon whereby pivotal downward and upward movement of the said handle moves the one rod longitudinally of the other to separate the said gripping portions or so that the said wedge portion may be 35 engaged by the said bridging member to force the gripping portions together, as and for the purpose specified.

Dated at Vancouver, B. C., this fifteenth day of April, A. D., 1914.

JOHN CARMICHAEL.
RALPH WHIPPS.
